UNITED STATES PATENT OFFICE.

JOHN G. HEPPDING, OF JERSEY CITY, NEW JERSEY.

DESIGN FOR A GEM-SETTING.

SPECIFICATION forming part of Design No. 20,870, dated June 30, 1891.

Application filed April 22, 1891. Serial No. 390,042. Term of patent 7 years.

To all whom it may concern:

Be it known that I, JOHN G. HEPPDING, a citizen of the United States, and a resident of Jersey City, in the county of Hudson, in the State of New Jersey, have invented a certain new Design for Bases for Gem-Settings, of which the following is a specification, reference being had to the accompanying drawings, forming part of the specification, in

which—

Figure I is a face view of a gem-setting base, showing my new design. Fig. II is a vertical transverse sectional view of the same on the line 2 2 of Fig. I. Fig. III is a bottom view of the same.

Similar letters of reference indicate corresponding parts.

The leading feature of my design consists in the radial ribs extending from the outer edge of the scalloped base toward the center.

A is the base for the gem-setting.

B B are the scallops or cup-shaped pockets, and C are the radial ribs or wings, the inner edges of which are slightly inclined upward and outward, their upper edges being slightly above the top edges of the scallops and slightly

inclined downward, said upper edges being cut off square to the side faces, as shown, and which ribs extend radially inward from the rim of the setting.

E are the curved radial ribs on the under side of the base.

Having thus described my invention, I claim as new and desire to secure by Letters Patent—

The design for a base for a gem-setting herein shown and described, the same comprising the scallop pockets B and the radial wings or ribs C, extending longitudinally across the centers of the pocket from the outer to the inner edges of the same, the upper edges of said wings or ribs C being slightly above the upper edges of the scallops, substantially as set forth.

In testimony that I claim the foregoing as my invention I have signed my name in presence of two subscribing witnesses.

JOHN G. HEPPDING.
